SUPERHEATER SUPPORT

Frederic Hall, Hale, England, assignor to The
Superheater Company, New York, N. Y.

Application February 15, 1934, Serial No. 711,381
In Great Britain February 21, 1933

6 Claims. (Cl. 248—68)

This invention has reference to steam superheater elements of the kind comprising a plurality of lengths of pipe, usually four lengths, arranged in a group and parallelly disposed and 5 extending into a smoke tube of a locomotive or like boiler and the invention relates particularly to means or devices for holding the constituent pipes of an element in their correct relation to one another and for supporting the elements in the 10 smoke tubes. For convenience of reference in this specification such means or devices will be designated as element bands and supports.

Various forms of element bands and supports have been proposed heretofore and certain of the 15 proposals have been carried into practice. The construction of element band and support most largely employed in practice consists of two strips of metal bent to shape, the one to provide a spacing member with pipe seats between the pipes of 20 the element and the other to provide a surrounding band to hold the pipes in position against such spacing member, the spacing member being riveted to the band intermediate the ends thereof and the ends of the band being riveted to one 25 another, appropriately formed and positioned steel blocks or feet being riveted to the band.

The present invention has for its object an improved construction of element band and support which shall not only be relatively cheap to manufacture, but also shall be such that it will be 30 robust and of a form permitting a more ready cleaning or removal from the surfaces of the element and flue tube of soot and other deposited furnace products, while, in addition, being such 35 that there will be less liability of choking of the flue tube at the support by deposits of soot or the like on or about the parts of the support.

It is another object of the invention to provide an element band which shall have the greatest 40 possible amount of its length in contact with the periphery of the pipes of the element, and thus avoid any relatively long portions of the band being out of contact with fluid cooled surface. Thus the band will be efficiently cooled and the 45 liability of it being burnt out will be reduced.

According to the present invention the element band is formed of a single strip of metal, such for example as mild steel, bent to shape to provide pipe embracing portions or seats, one for 50 each pipe of the element, the pipe embracing portions when the band is in place on the element each exceeding one-half of a cylinder and alternating in the length of the band with the pipe embracing portions or seats are pipe spacing portions or bridges, the ends of the strip after the

band has been closed on the element being secured together and serving to space two pipes of the element.

An element band according to this invention may be provided with appropriate feet for supporting the element in the smoke tube, and such feet may be separately formed and secured to the element band or may be formed by bending or folding up the metal strip from which the band is formed. Preferably the feet would be riveted to the band as in the known construction of element band and support already referred to, but if desired the feet may be welded to the band. The ends of the strip or band are secured to one another in any appropriate manner, as for example by welding with or without an intervening fillet or filler piece or by riveting.

In an element band, or band and support, according to the invention the employment of an internal spacing member is avoided, as is also the riveting of the said spacing member to the strip.

The band according to the present invention is placed on the element after the several lengths of pipe comprised in the element have been united by the return bends to form the complete element, the said pipes being gripped by an appropriate machine or means while the band and support are being applied thereto.

A band and support for a four-pipe element, 30 which is the type of element now most largely employed in superheaters for locomotive boilers, is shown in the accompanying drawing and will be described hereinafter as an example of an embodiment of the invention: it is to be understood that the invention is not restricted to bands, or bands and supports, for four-pipe elements, as bands and supports may be made according to the invention for elements comprising a lesser or a greater number of parallelly disposed pipe lengths in the flue tube. 40

In the accompanying drawing,

Fig. 1 shows in elevation an element band and support for a four-pipe element, the band being shown in the shape it takes before it is applied to the pipes of the element, 45

Fig. 2 is a view showing the band illustrated in Fig. 1 applied to the four pipes of a locomotive superheater element disposed in a flue tube, 50

Figs. 3, 4, and 5 are fragmentary sectional views, the sections being taken on the lines 3—3, 4—4, and 5—5 respectively of Fig. 2 and looking in the directions of the arrow points, and

Figs. 6, 7 and 8 are fragmentary views illus- 55

trating modifications in constructional details which will be described.

In manufacturing the band and support for a four-pipe element, according to the method of carrying the invention into practice illustrated by Figs. 1 to 5, a strip of metal of appropriate width and gauge is bent backwards and forwards upon itself into a more or less quadrifol shape so that four pipe-embracing portions or seats 1, 2, 3, and 4 are formed, each exceeding one-half of a cylinder and forming, for example, approximately three-quarters of a cylinder, the pipe seats 1 . . . 4 alternating with bridges 5, 6, and 7 forming pipe spacing portions. These three bridges are formed in bending the strip, and a fourth bridge is formed, after the strip has been placed on the element pipes and closed down thereon, by welding a fillet 8 between the end portions 9 and 10 of the strip, the end portions thus being secured together. The bridges 5, 6, 7 formed between the pipe seats by bends in the strip, preferably have their rigidity increased in some appropriate manner. As shown in Figs. 1 to 4 the bridges are stiffened by forming across each bridge one or more depressions 11 in the metal after the manner of corrugations.

Alternatively the bridges may be strengthened as shown in Fig. 6 by deposits 12 of welding metal in the recesses of the re-entrant portions between the pipe seats.

In Fig. 2 of the drawing, 13, 14, 15, and 16 are the pipes of a superheater element, 17 being the smoke tube in which the said pipes are disposed. As in the usual four-pipe locomotive elements, the space between the lower pipes 14, 15 is 35 greater than the spaces between such pipes and the upper pipes 13, 16 respectively, and also is greater than the space between the upper pipes themselves. Consequently, the bridge 6 of the band which lies between the lower pipes 14 and 15 and which is mid-way of the length of the strip will be wider than the other bridges 5 and 7. If desired, such wider bridge 6 may be strengthened by depressing or corrugating the metal whilst the narrower bridges 5, 7 may be strengthened by deposits of weld metal as described with 45 reference to Fig. 6.

Where deposits of weld metal are employed to stiffen or reinforce the bridges of the element band such deposit of weld metal may be effected either before or after the band is fitted on the element.

In manufacturing the element band shown in Fig. 2 the strip is bent to form the bridges 5, 6, 55 and 7 and to partially shape the seats or pipe embracing portions 1 . . . 4 for the pipes, the end portions of the strip being left extending towards one another so that the band has approximately the form shown in Fig. 1. In applying the band 60 to the element the bridges or spacing portions 5 and 7 of the band are forced inwardly to close the band over the lower pipes 14, 15 of the element. Thereafter the end portions 9, 10 are bent or hammered over so that the upper pipe 65 embracing portions or seats 1 and 4 are closed on to pipes 13 and 16 and the band snugly embraces the respective pipes. Between the end portions 9 and 10 which are themselves dependent 70 between the upper pipes 13, 16, the fillet 8 which is preferably somewhat wedge-shaped in cross-section, is driven into place and its upper portion welded to the adjacent portions of the band as at 18. A unitary structure is thus formed, which securely holds the pipes in correct 75 relation to one another, but which presents

a relatively small obstruction to the passage of combustion gases through the smoke tube.

Usually the element band will be provided with feet to support the element in position in the smoke tube 17. In the band shown in Figs. 1 and 2 separately formed solid feet 19 are attached to the outer side of the portions 2, 3 of the band of the band embracing the lower pipes 14 and 15 of the element substantially mid-way between the respective bridges 5, 6, 7. Preferably the solid 10 feet are riveted to the band as indicated in Figs. 1, 2, and 5, but if desired they might be welded to the band, or be both riveted and welded thereto. Each foot 19 may consist of a single block of metal of appropriate dimensions, but 15 conveniently it comprises a main or face portion adapted to contact with the flue tube and an intermediate packing or filler piece 20 as clearly shown in Fig. 5. Thus by varying the thickness of the piece 20 the spacing of the pipe from the 20 inner surface of the flue tube may be varied. The foot 19 shown in Fig. 5 is of greater length than the width of the strip so that it projects at either side of the strip or band and its surface facing the flue tube may be inclined upwardly at 25 the extended end portions as shown.

If desired, instead of forming the feet separately and attaching them to the band they may be an integral part of the band, being formed by appropriately bending or folding the strip of 30 metal in manufacturing the band to form outwardly projecting portions. For example, the strip may comprise bends more or less of a flat U-shape, as shown at 21 in Fig. 6, to provide feet which will give a substantial bearing surface on 35 the flue tube. To render the feet 21 rigid and prevent the band opening out at the bent portions forming such feet, one or more depressions or corrugations 22, similar to the depressions 11 in the bridges 5, 6, are preferably formed in each 40 bent portion 21.

While it is considered preferable to employ the separate fillet 8 for completing the bridge between the pipe embracing portions 1 and 4 of the band, one extreme end portion of the strip 45 may be folded back on the strip as shown at 23, Fig. 7, so that when the end portions of the strip are driven into the space between the pipes 13 and 16, the folded back portion 23 will take the place of the fillet 8. The portion 23 would 50 be welded to the pipe embracing portions 1 and 4 in a similar manner as described in relation to the fillet 8. If the spacing of the pipes 13, 16 is relatively wide both ends of the strip may be folded back and the folded back portions welded 55 to one another and to the respective pipe embracing portions.

Where it is desired to secure the ends of the strip to one another by riveting, a strip of greater length may be employed than where the ends 60 are secured together by welding; the end portions of the strip may be bent or folded back on themselves so that when the folds are forced, as by hammering, into position between the two upper pipes the extreme end portions of the 65 strips project upward and lie snugly against one another in position to be riveted together.

Where it is desired to increase slightly the grip of the bands on the pipes the pipe spacing or bridge portions 5, 6, and 7 may be carried 70 further towards the centre of the band. In this case the ends of such portions may have a somewhat bulbous appearance as shown at 24, Fig. 8. It will be appreciated that to place a band so formed on the element the pipes would have 75

to be sprung apart in forcing the bridges into position to allow the bulbous end portions to pass between the pipes. A bridge formed in the manner shown in Fig. 8 may be strengthened by the depression 11 as described with reference to Figs. 1 . . . 4, or by a deposit of welded metal as described with reference to Fig. 6.

In order to maintain the element band and support according to the present invention in position longitudinally of the element small deposits 10 or spots of welding metal may be made on one or more of the pipes of the element at opposite sides of the band, but at a sufficient distance therefrom to prevent the band being united by welding 15 to the pipe or pipes.

The element band according to the present invention is more particularly intended for use with a four-pipe element, but, as already indicated, bands comprising seats for three pipes only or for 20 more than four pipes might be formed by bending a single strip of metal substantially in the manner herein described, and securing the ends of the strip together.

Other modifications might be made without 25 departing from the invention.

What I claim is:

1. A band for steam superheater elements of the kind indicated consisting of a strip of metal 30 bent to provide four pipe embracing portions alternating in the length of the strip with pipe spacing portions, each pipe embracing portion

when the band is in place on the pipes of the element exceeding one-half of a cylinder and the ends of the strip after the band has been placed on the element being secured together and spacing two pipes of such element.

2. An element band as claimed in claim 1 having the spacing portions between the pipe seats reinforced.

3. An element band as claimed in claim 1 having at least one of the spacing portions stiffened 10 by forming across it a depression after the manner of a corrugation.

4. An element band as claimed in claim 1 having at least one of the spacing portions stiffened 15 by depositing welding metal in the recesses of the re-entrant portions of the band between the pipe embracing portions thereof.

5. An element band as claimed in claim 1 having a metal filler piece inserted between the end 20 portions of the strip after they have been positioned between the appropriate two pipes of the element, the end portions and filler being welded together.

6. An element band as claimed in claim 1 having a relatively short portion at one end of the 25 strip folded back on the strip, the folded-back portion after the end portions of the strip have been driven into position between the appropriate two pipes, being welded to the adjacent portions of the strip.

FREDERIC HALL.
